UNITED STATES PATENT OFFICE

2,574,146

CARRYING RECEPTACLE

Melvin Gottesman, New York, N. Y., assignor to
 Mel-Ton Bags, Inc., New York, N. Y., a corporation of New York

Application June 25, 1951, Serial No. 233,393

1 Claim. (Cl. 150—29)

1

The present invention relates to a carrying receptacle which is illustrated for example by a handbag.

Heretofore, in carrying receptacles such as handbags, pouches, purses and the like carried in the hand, the frames therefore were not connected or articulated with the handle thereof and separate locking means were provided.

Thus, in prior carrying receptacles, the pouch or compartment thereto lent itself to being opened by pick-pockets when it was carried loosely by the handle in the customary manner.

Further, handbags and the like of the prior art, since they required separate frames for the pouch or compartment that were unconnected with the handle, were comparatively more difficult and expensive to manufacture.

In the present invention, I contemplate the provision of a handbag and the like in which the members forming the handle are connected to the members forming the frame of the pouch or compartment of the handbag.

Further, in the handbag and the like embodying my invention, the handle itself forms a lock to the pouch or compartment of the bag so that it cannot be opened so long as the bag is carried in the usual manner by the handle. Therefore, the handle constitutes a safety catch against inadvertent and unknowing opening of the bag, as by pick-pockets.

The present invention therefore contemplates the provision of a handbag and the like in which the frame, handle and lock constitute a unitary structure instead of the separate and individual unconnected members of prior handbags and the like.

The present invention contemplates the provision of a handbag and the like which is of a comparatively simple construction and which is relatively inexpensive to manufacture and assemble.

These, other and further objects and advantages of the present invention will be clear from the following description and the drawing appended thereto, in which

Fig. 1 is a front elevation of a handbag, pursuant to my invention, the handbag being closed

Fig. 2 is a side view thereof, the handbag in partially opened condition

Fig. 3 is a top plan view, the handbag in fully opened condition and one of the handle elements broken away and the fabric of the handbag at one side thereof also broken away to disclose a frame member.

Referring now to the drawing, the pouch or

2

bag 10, which may be made of any suitable material, such as any fabric, leather, beaded, straw, plastic, etc., and of any shape or form, that shown in the drawing being for illustration only, is suspended at each side from the opposed frame members 12 and 14 formed preferably from metallic rods.

Each edge of the handbag compartment 16 (see Fig. 3) is provided with a pocket open at each 10 end so that the frame members or rods may be thrust therethrough with their preferably threaded ends extending outside thereof.

The handle of the handbag comprises the two members 18 and 20 having the horizontal elements, which are grasped by the hand to hold the bag and which are bent to form at each end of the handle the downwardly extending connecting elements 22 and 24.

These elements 22 and 24 are provided with 20 suitable openings at their ends through which the preferably threaded ends of the frame members or rods 12 and 14 extend and are thus mounted on the frame members or rods 12 and 14 at each end thereof so that they may be freely 25 pivoted thereon when the bag is opened or closed, as I shall describe.

In order to hold the handle members 18 and 20 on the frame members or rods 12 and 14 and prevent the latter from inadvertently being removed from the pockets at the sides of the bag, 30 I provide any suitable means such as the hexagonal nuts 26.

Intermediate the horizontal elements of the members 18 and 20 and the openings at the lower 35 ends of the downward elements 22 and 24, I connect the latter together by the pivot pins 28 and 30.

As an inspection of Figs. 2 and 3 will indicate the elements 22 and 24 are disposed crosswise 40 of each other and when the carrying receptacle is open, the horizontal elements 18 and 20 are located on opposite sides of the frame members 12 and 14 to which they are connected.

As will be seen, the handle members are articulatedly connected with the frame members so 45 that opening or closing the handle correspondingly opens and closes the frame or carrying receptacle.

The pivot pins are provided in any satisfactory manner, as by peening, with heads to prevent the pins from inadvertent removal from their positions.

If desired, in order to assist opening the bag, the side tabs 32 and 34 may be provided along 55 each upper edge of the pouch or bag 10.

In order to close the bag, one of the horizontal handle elements or members 18 and 20 is positioned under the other where it is preferably frictionally held.

In order to accomplish this function, the downward elements 22 and 24 are rotated about the pivot pins 28 and 30.

This movement moves the corresponding frame members or rods 12 and 14 toward each other, since the open ends of the downward handle frame members are pivoted on the frame members, thereby closing the pouch or bag 10.

So long as the horizontal handle elements or members 18 and 20 are held by the hand, the pouch or bag 10 is held closed and cannot be opened without the consent of the holder.

To open the bag, the handle is released and the frame members or rods 12 and 14 pulled apart or separated, as by the side tabs 32 and 34, though it will be understood that the side tabs are not required for this purpose since the horizontal elements or members may themselves be moved apart. Opening of the carrying receptacle may also be accomplished through the manual separation of the horizontal elements 18 and 20.

Separation of the horizontal members or elements will pivot the downward elements 22 and 24 about the pivot pins 28 and 30 through the intermediate position illustrated in Fig. 2 into the fully open position illustrated in Fig. 3.

This separation of the handle elements, since they are pivotally mounted on the frame members or rods 12 and 14, forces the latter apart to open the pouch or bag 10 thereby making accessible the interior of the compartment 16 of the handbag.

It will now be recognized that I have provided an articulated connection between the handle and the frame of a carrying receptacle, such as a handbag or the like so that corresponding movement of the handle members will open and close the bag or the like and which handle constitutes a lock therefor.

It will now be further recognized that the handle, frame member and lock constitute a

unitary structure which is relatively simple and comparatively inexpensive to manufacture.

While I have described in specific detail an illustrative embodiment of my invention, it will be understood that other modifications will now occur to those skilled in the art without departing from the spirit and scope of my invention.

I claim:

In combination, a handbag open at its top and including a pair of side walls, rods extending along the upper edge portions of the side walls, and a pair of inverted substantially U-shaped members, the legs of one of said members intersecting the intermediate portions of the corresponding legs of the other U-shaped member and being pivotally connected at the point of intersection, the free ends of the legs extending outwardly and being secured to the outer ends of the respective rods, whereby the top of the bag will be closed when the U-shaped members are brought together and disposed in substantially the same plane, the crown portions of said U-shaped members forming a carrying handle for the handbag, the leg portions of one U-shaped member above the pivot points for said members, being shorter than the corresponding leg portions of the other U-shaped member.

MELVIN GOTTESMAN.
